UNITED STATES PATENT OFFICE.

JAMES W. KENYON, OF MUSKEGON, MICHIGAN, ASSIGNOR TO THE SHAW-WALKER COMPANY, A CORPORATION OF MICHIGAN.

DRAWER-SLIDE.

1,189,580.

Specification of Letters Patent. Patented July 4, 1916.

Application filed May 4, 1914. Serial No. 836,052.

To all whom it may concern:

Be it known that I, JAMES W. KENYON, a citizen of the United States, residing at Muskegon, in the county of Muskegon and 5 State of Michigan, have invented new and useful Improvements in Drawer-Slides, of which the following is a specification.

My present invention relates to devices known as drawer slides whereby cabinet 10 drawers may be easily drawn out and pushed back; and its object is to provide a device of that character which shall be very easy of operation; and further, whose members shall be readily assembled and disassembled; 15 and further, which shall be improved in various particulars hereinafter appearing. This object is attained by, and the invention finds preferable embodiment in, the structure hereinafter described and illustrated by 20 the accompanying drawings, in which:—

Figure 1 is a perspective view of a cabinet to which my invention is applied; Fig. 2 is a view of my drawer slide carried on the inner surface of a side of such cabinet; Fig. 25 3 is an enlarged vertical sectional view of the same taken on line 3—3 of Fig. 2, and showing a fragment of the drawer. Fig. 4 is a like view taken on line 4—4 of Fig. 2; Fig. 5 is a like view taken on line 5—5 of 30 Fig. 2; and Fig. 6 is a view similar to Fig. 2 but showing the members extended to dis- 35 assembling position.

The primary slide-member 1 carried on the inner surface of the side 2 of a cabinet 3, 40 has upper and lower longitudinal guides 4 and 5 in which is adapted to travel the intermediate slide-member 6, being mainly supported medially of its length by the guided member or roller 7 and being also supported when the drawer 8 is pushed in by the inner roller 9 both which travel in the lower guide 5: A suitable guided member, as the lug 10 or roller 11, or both as shown, travels in the upper guide 4, such 45 roller 11 serving as an upward thrust-resisting member when the drawer is drawn out.

The ultimate slide member 12 which carries the drawer 8 has a sustaining flange 13 supported by and traveling on said roller 7 and the roller 14 and, when the drawer is pushed in, on the roller 9, the upward-thrust of such ultimate slide-member when drawn out being resisted or sustained by a 50 roller 15. A suitable stop 16 against which

the lug 10 strikes, limits the outward movement of the intermediate slide-member, and the ultimate slide member's outward movement is limited by the L-shaped stop 17 pivoted on the intermediate member and adapted to be turned into its stop position shown in the drawings when it is engaged by the lug 18 in the drawn-out position of the drawer, and also to be turned on its pivot out of such stop position; when this is done, the drawer with the ultimate members 55 may be entirely withdrawn from the cabinet, whereupon the intermediate slide-members may also be withdrawn by moving them to the position shown in Fig. 6, wherein the roller 7 registers with a gap 19 in the side flange or wall 20 of the lower guide 5: the lower part of this roller may now be moved through this gap, and by further withdrawing the intermediate member till the 60 roller 9 registers with the gap, it too may be moved through it, thus removing the intermediate-slide member entirely.

A suitable buffer 21, preferably of rubber, carried at the inner end of the intermediate member, may be provided to receive the stroke of the back 22 of the cabinet on one side and that of the inner end of the drawer on the other, when the drawer is pushed in. The upper and lower guides 65 4 and 5 are off set from the face of the primary slide-member 1 (by having their inner wall spaced from the inner surface of said member as shown in Figs. 3, 4 and 5) sufficiently to hold the intermediate slide member 6 out of contact therewith, whereby friction is minimized; and the hubs 23 provided on one side the 70 lower rollers allow free movement of the retaining flange 24 of the ultimate member 95 by spacing it from the intermediate slide-member.

It will be seen that by my arrangement of the slide-members with their flanges, the rollers are approximately in the same vertical plane, the intermediate slide-member and the sustaining flange of the ultimate slide-member being thus located within the lateral dimension and also the vertical dimension of the primary slide-member, thus 100 economizing space.

It will be seen (particularly in Figs. 2 and 6) that the roller 7 is loosely mounted on the intermediate slide-member 6, so that its axis has a vertical "play" on or relatively 105

to such slide-member. The effect of this arrangement is, that when the drawer is pulled out far enough for the roller 14 to pass outside of and drop off of the guide 5, the intermediate slide-member's outer end is permitted to fall slightly, (such member turning on the axis of the roller 9 as a fulcrum), and the horizontally-extending flange 13 of the ultimate slide-member 12 (which carries the drawer) will be pressed or pinched by gravity between the roller 7 below and the roller 15 above, thus causing the roller 7 to tractionally engage said flange, so that the drawer's motion in either direction moves the intermediate slide-member at half speed.

Not confining myself to details of construction shown or described, I claim:—

1. In a device of the character described, a primary slide-member having upper and lower guides one of which has a gap through its lateral wall, an intermediate slide-member traveling in said guides and having a guided member, and an ultimate slide-member movably supported on the in-

termediate slide-member, said guided member of the intermediate slide being adapted in one position of such intermediate slide to be moved outwardly through said gap from the guide in which it moves.

2. In a device of the character described, a primary slide-member, an intermediate slide-member slidable on the primary slide-member, and an ultimate slide-member slid-able on the intermediate slide-member; one of said slide-members having a guide with a lateral wall and a gap through said wall, and another of said slide-members having a guided member slid-able in said guide and adapted in one position to be moved outwardly through said gap from the guide in which it slides.

In testimony whereof I have hereunto set my hand in presence of two subscribing witnesses.

JAMES W. KENYON.
